US00D747587S

(12) **United States Design Patent**
Stauff et al.

(10) **Patent No.:** US D747,587 S
(45) **Date of Patent:** ** *Jan. 12, 2016

(54) **SHOPPING CART**

(71) Applicant: **Bemis Manufacturing Company**,
Sheboygan Falls, WI (US)

(72) Inventors: **Richard Stauff**, Plymouth, WI (US);
Gary Vande Berg, Fox Lake, WI (US);
Roy Watson, Lisbon, OH (US)

(73) Assignee: **Bemis Manufacturing Company**,
Sheboygan Falls, WI (US)

(*) Notice: This patent is subject to a terminal disclaimer.

(**) Term: **14 Years**

(21) Appl. No.: **29/469,618**

(22) Filed: **Oct. 11, 2013**

CLAIM

We claim the ornamental design for a shopping cart, as shown and described.

DESCRIPTION

FIG. 1 is a perspective view of a shopping cart showing our new design.

FIG. 2 is a right side view of the shopping cart shown in FIG. 1.

FIG. 3 is a left side view of the shopping cart shown in FIG. 1.

FIG. 4 is a top view of the shopping cart shown in FIG. 1.

FIG. 5 is a front view of the shopping cart shown in FIG. 1; and,

FIG. 6 is a back view of the shopping cart shown in FIG. 1. The bottom views are not a part of the claimed design.

The broken lines shown in the figures are included for the purpose of illustrating environment and forms no part of the claimed design.

1 Claim, 5 Drawing Sheets
